UNITED STATES PATENT OFFICE.

PERLEY G. TILTON, OF MELROSE, MASSACHUSETTS.

DESIGN FOR A WATERPROOF CAP-COVERING.

44,042.

Specification for Design.

Patented May 13, 1913.

Application filed November 14, 1912. Serial No. 731,427. Term of patent 7 years.

To all whom it may concern:

Be it known that I, PERLEY G. TILTON, a citizen of the United States, residing at Melrose, in the county of Middlesex and State of Massachusetts, have invented a new, original and ornamental Design for Waterproof Cap-Coverings, of which the following is a specification, reference being had to the accompanying drawing, forming part thereof.

Figure 1 is a side view of a cap covering,

showing my new design. Fig. 2 is a front view of the same.

I claim:

The ornamental design for a waterproof cap covering, as shown.

In testimony whereof I affix my signature, in presence of two witnesses.

PERLEY G. TILTON.
